CLAIM

We claim the ornamental design for a saw blade, as shown and described.

DESCRIPTION

FIG. 1 is a perspective view of a saw blade embodying the invention.

FIG. 2 is a side view of the saw blade of FIG. 1.

FIG. 3 is an enlarged view of a portion of the saw blade of FIG. 1.

FIG. 4 is a perspective view of another saw blade embodying the invention.

FIG. 5 is a side view of the saw blade of FIG. 4; and, FIG. 6 is an enlarged view of a portion of the saw blade of FIG. 4.

The evenly spaced broken lines in FIGS. 1-2 are for the purpose of showing portions of the saw blade that form no part of the claimed design.

The long and short broken lines in FIGS. 1-3 that define the bounds of the claimed design form no part thereof.
